United States Patent Office

Des. 181,299
Patented Oct. 29, 1957

181,299

AIRCRAFT RUNWAY VACUUM CLEANER

Lewis S. List, Valley Stream, N. Y., assignor to United States Hoffman Machinery Corporation, New York, N. Y., a corporation of New York

Application September 17, 1956, Serial No. 42,974

Term of patent 14 years

(Cl. D14—3)

Fig. 1.

Fig. 2.

Figure 1 is a perspective view of an aircraft runway vacuum cleaner seen from the left side, embodying my new design;

Figure 2 is a rear view;

Figure 3 is a top view; and

Figure 4 is a left side view, the side opposite being substantially the same.

The essential features of my design reside in those portions shown in full lines.

I claim:

The ornamental design for an aircraft runway vacuum cleaner, substantially as shown and described.
